CLAIM

The ornamental design for a railroad car coupler assembly
knuckle pin, as shown and described.

(51) **LOC (13) Cl.** **12-03**

DESCRIPTION

(52) **U.S. Cl.**

FIG. 1 is a first front perspective view of a railroad car
coupler assembly knuckle pin showing my new design.

USPC **D12/48**

FIG. 2 is a second front perspective view of the railroad car
coupler assembly knuckle pin.

(58) **Field of Classification Search**

USPC D12/36-51; D8/382, 356, 388, 391
CPC ... B61G 7/00; B61G 3/04; B61G 3/06; B61G
3/22

FIG. 3 is a front side view of the railroad car coupler
assembly knuckle pin.

See application file for complete search history.

FIG. 4 is a rear side view of the railroad car coupler
assembly knuckle pin.

(56) **References Cited**

FIG. 5 is a right side view of the railroad car coupler
assembly knuckle pin.

U.S. PATENT DOCUMENTS

FIG. 6 is a left side view of the railroad car coupler assembly
knuckle pin.

440,586 A * 11/1890 Eastwick, Jr. B61G 3/04
213/155

FIG. 7 is a top view of the railroad car coupler assembly
knuckle pin; and,

732,887 A * 7/1903 Parish B61G 3/04
213/155

FIG. 8 is a bottom view of the railroad car coupler assembly
knuckle pin.

1,093,858 A * 4/1914 Janney B61G 3/04
213/155

The broken lines shown in the drawing views illustrate
portions of the railroad car coupler assembly knuckle pin
that form no part of the claimed design.
